UNITED STATES PATENT OFFICE.

ARTHUR PEMBERTON WOOD, OF HALE, AND ROBERT STAFFORD McLEOD, OF DIDSBURY, NEAR MANCHESTER, ENGLAND.

APPARATUS FOR ELECTRICALLY OPERATING PLANING-MACHINES AND THE LIKE RECIPROCATING TOOLS.

1,147,585.

Specification of Letters Patent.

Patented July 20, 1915.

Application filed December 27, 1913. Serial No. 809,126.

To all whom it may concern:

Be it known that we, ARTHUR PEMBERTON WOOD, a subject of the King of Great Britain, and residing in Hale, in the county 5 of Chester, England, and ROBERT STAFFORD McLEOD, a subject of the King of Great Britain, and residing in Didsbury, near Manchester, in the county of Lancaster, England, have invented certain new and 10 useful Improvements in Apparatus for Electrically Operating Planing-Machines and the like Reciprocating Tools, of which the following is a specification.

This invention relates to switch gear by 15 means of which the movement of a reciprocating tool such as a planing machine is adapted to automatically control the movement of the electric motor by which the feed screw of the tool is operated. In such 20 gear it is necessary, after a cutting stroke has been made, that the motor by which the feed screw is actuated should be rotated through a definite angular amount, and such rotation should preferably take place 25 after the return stroke of the tool has been made, and be completed before the succeeding cutting stroke is commenced.

Reciprocating tools are provided with an adjustable tappet gear by means of which 30 movement is imparted, at the end of the cutting stroke or at the end of the return stroke, as may be preferred, to a suitable movable piece such as a tappet rod, and according to the present invention the movement so given to the said part, say a tappet rod, is utilized to close the energizing circuit of the feed motor, whereupon the motor commences to rotate; the amount of rotation of the motor required depends upon the 35 feed which it is desired to give to the tool, and according to the present invention, the movement of the electric motor itself, while effecting the predetermined amount of feed, is utilized to open the energizing circuit of the motor, and if necessary to actuate an 40 electrically operated brake, or to close the circuit of a brake resistance in series with the motor armature.

The invention is applicable generally for 50 controlling the energizing circuit of the motor; such circuit may be the main motor circuit, but preferably the arrangement for operating a feed motor to which the invention

is applied, is as follows:—A constantly driven generator is provided, the armature 55 of which is connected in series with the armature of the feed motor. The field winding of the generator is adapted to be connected across a suitable source of potential by means of switch gear operated by the 60 joint action of the machine tappet gear and the movement of the feed motor. When the field winding of the generator is connected to a suitable source of potential, the feed motor is supplied with current from the 65 generator, and rotates, when the said circuit is opened, the supply of current ceases and the motor stops. The switch gear described hereinafter is adapted to control the said field winding of the generator. 70

The invention is illustrated in the accompanying drawings in which—

Figure 1 shows the general arrangement as applied to a planing machine; Fig. 2 is a diagrammatic view of the electrical connections; Fig. 3 is a diagrammatic view of the switch gear and its connections; Figs. 4 and 5 are, respectively, an elevation partly in section and a sectional side elevation of one form of switch operating gear; Figs. 6 and 7 show a modification; Fig. 6^a is a fragmentary elevation of the cam disk S²; Figs. 8, 9 and 10 are views of a suitable form of speed changing gear and resistance control gear. 85

Referring first to Fig. 1;—A is the planing machine, a¹ being the tool box, a² the cross slide and B the feed screw; a³ is the planer table and a⁴ and a⁵ are the adjustable tappets which operate a tappet lever 90 a⁶ in the usual manner. C is the tappet rod. M is an electric motor the armature spindle of which is geared to the feed screw B, and also geared through a speed changing gear box N' to one of two moving parts by the 95 joint action of which parts as hereinafter described the switch E (Fig. 2) is operated; the other moving part is operated by the tappet rod C.

Fig. 2 shows the preferred arrangement 100 for energizing the motor M. P and Q are two mains which are connected to any suitable source of potential, such for example as a generator R. G is a generator driven at constant speed by any suitable means and 105 its armature is connected in series with the

motor M; the field winding G^s of the generator is adapted to be connected across the main P and Q through the contacts e¹ by the switch E, an adjustable resistance F, and a reversing switch H, and it is provided with a discharge or buffer resistance G^b, K is a braking resistance adapted to be connected across the motor armature through the contacts e² by the switch E. M^s is the motor field winding which may be connected across P, Q, and O is a switch by means of which the winding G^s can be connected across P, Q, independently of the switch E and resistance F.

15 Referring now to Fig. 3;—The switch E is carried at the end of an arm N pivoted on the spindle n; the arm N carries a pinion n¹ which gears with an internally toothed wheel S and an externally toothed wheel T.

20 The wheel T is driven by the pawl t¹ on the ratchet lever t² by the tappet rod C, and the wheel S is driven by a wheel s² gearing with teeth on the periphery of S; on the spindle s¹ change wheels s³, s⁴ are mounted

25 and the wheel s⁵ on the lever s⁶ is adapted to gear with s², s³ or s⁴, and also gears with the pinion s⁷ which is keyed on the spindle m¹ driven by direction changing gear from the motor spindle m. When the wheel T

30 is operated by the tappet gear the pinion n¹ and lever N carry the switch E around till it connects the contacts e¹ and connects the winding G^s across the mains P, Q; this causes the motor to rotate whereupon the

35 movement of the wheel S driven by the motor in the opposite direction moves the pinion n¹, lever N and switch E back till it closes the contacts e² and puts the braking resistance across the motor armature

40 which brings the latter to rest quickly. The change speed gear enables any desired speed ratio to be maintained between the feed screw B to which the motor is geared, and the wheel S. The lever s⁶ carries a rheostat

45 switch contact s⁸ the position of which in relation to the resistance contacts depends upon the position of the lever s⁶ so that the magnitude of the resistance F' depends upon the number of revolutions made by the

50 motor each time the feed is effected.

In Figs. 4 and 5 the arrangement is similar to that described, except that instead of spur wheels T and S, bevel wheels T' and S' are employed and a bevel pinion n² is mounted on the lever N' which carries the switch E'. As before E' closes the contacts e¹ when moved in the one direction by the wheel T' operated by the tappet gear, and closes the contacts e² when moved in the opposite direction by the wheel S' operated by the feed motor. The wheel T' is operated by means of the ratchet wheel t⁴, pawl t⁴ and pawl lever t⁵ reciprocated by the tappet rod C'; t⁶ is a locking pawl. By slotting the lever t⁵ as at t⁷, and operating

it by means of a lever W also slotted as at w¹ and connected to the lever t⁵ by a pin w², the angular movement of t⁵, for a given movement of W, may be adjusted by alteration of the position of the pin w² in the slot w¹ in which slot it is held fixed by a nut w³. The lever W has a short arm w⁴ carrying a roller w⁵ which roller fits in a slot w⁶ in the tappet rod C'; a portion of the slot is disposed obliquely to the direction of motion which C' is constrained to take by the guides w⁷. C' is reciprocated by the planer tappet lever a⁸ in any convenient manner. The ends w⁸ of the slot w⁶ are made parallel to the direction of motion of the rod C' so that the movement of the lever W is effected by the operation of the roller w⁵ after the beginning and before the end of the movement of the tappet rod C'; in this way the actuation of the lever W is positive and definite irrespectively of any lost motion or back-lash in the tappet gear or of any over-running of the tappet gear. The locking lever t⁶ is connected to or made integral with the lever W. h³ is a spindle having an end crank pin h⁴ adapted to move the wheels m⁴ and m⁵ when the direction of the motor has to be reversed to reverse the motion of the feed screw, and H' is a reversing switch adapted to change the direction of rotation of the motor. The motor spindle m is connected by a speed change gear box, as shown in Figs. 8, 9 and 10 and described hereinafter, to the spindle m² which is connected by direction changing bevel gear m³, m⁴, m⁵, to the spindle m⁶ of which the wheels m⁵ and m⁴ are keyed.

Referring now to Figs. 6 and 7; the motor spindle is connected by speed changing gear to the shaft m⁷, and the latter is connected by direction changing gear m⁸, m⁹ and m¹⁰ to the spindle m¹¹ on which is mounted a cam disk S² to which angular movement is thus given by the motor M. In line with the spindle m¹¹ is a rotatable part T² mounted in the bearing t¹⁰. T² carries a transverse spindle t¹¹ on one end of which is a lever t¹² adapted to be actuated by the edge s¹⁰ of the cam plate S²; and on the spindle t¹¹ is a lever t¹³ which engages with a stem t¹⁴ passing through an axial bore in T² and carrying the switch E². When T² is rotated by the tappet gear C², pawl lever t¹⁵, pawl t¹⁶ and ratchet t¹⁷, relatively to S² in the direction of the arrow Z, the lever t¹² moves clear of the edge s¹⁰ of the cam plate S² and the spring e³ moves the stem t¹⁴ into a position in which the switch E² connects the contacts e¹. The motor now rotates and carries the cam disk S² around in the same direction as that in which T² was moved; at the end of the motor movement the edge s¹⁰ of the cam disk S² engages with the lever t¹² rotating the spindle t¹¹ and lever t¹³.

- which latter actuates the stem t^4 and moves the switch E^2 out of contact with the contacts e^1 and into a position in which it connects the contacts e^2 and closes the brake control circuit. The angular movement imparted to the part T^2 can be regulated by means which vary the movement imparted to the ratchet t^17 . h^1 is a spindle having an end crank pin h^2 adapted to move the wheels m^9 and m^{16} when the direction of the motor has to be reversed to reverse the motion of the feed screw, and H is a reversing switch adapted to change the direction of rotation of the motor.
- 15 Referring now to Figs. 8, 9 and 10 which show the mode of construction of the change speed gear for the motor operated part of the switch gear, and the rheostat switch. Fig. 8 is a plan partly in section and with the cover of the gear box removed. Fig. 9 is a side elevation and Fig. 10 is a transverse section on the line X, X, of Fig. 10, showing the hand lever in position with the intermediate wheel gearing with the largest diameter change wheel. The spindle p^{10} is driven by the change wheels p^1 , p^2 , p^3 , etc., through the intermediate wheel m^{28} mounted on the lever m^{15} which is driven by the wheel m^{24} feathered on the spindle m^{25} which is driven by a clutch m^{19} and m^{20} from the spindle m which may be a motor spindle or a continuation thereof. The spindle m^{25} is pressed to the left by the spring m^{16} (exerting pressure through the ball race m^{17} and adjusted by the screw m^{18}) so that the clutch member m^{19} on the spindle m^{25} normally engages with the clutch member m^{20} on the shaft m which latter clutch member and shaft m are fixed axially. The clutch member m^{19} is attached to a plate m^{13} which forms the armature of an annular magnet m^{21} energized by coil m^{22} . When it is desired to actuate the feed screw for traversing purposes, the traversing switch O (see Fig. 2) is closed, whereupon the circuit of the magnet winding m^{22} is energized and the spindle m^{25} is disconnected from the spindle m by the axial movement of the armature m^{13} and the clutch member m^{19} . The lever m^{15} is pivoted on the boss of the pinion m^{24} so that the lever and pinion can slide on the spindle m^{25} . The switch operating part actuated by the motor is driven by the spindle p^{10} through direction changing bevel gear as shown in Figs. 4 and 5, and 6 and 7. The gear is inclosed by a casing N , and the handle of the lever m^{15} projects through an opening in the casing which opening is provided with steps n^1 and with locking holes n^2 to take the pin n^3 on the locking lever n^4 (see Fig. 10).
- It will be seen from an inspection of Figs. 8, 9 and 10 that by moving the lever to the appropriate step and locking it in the appropriate locking hole the intermediate wheel m^{23} may be geared with any of the change wheels p^1 , p^2 , p^3 , etc., to give the desired velocity ratio between the spindle p^{10} and the spindle m^{25} .
- 10 F' (Fig. 8) is the regulating resistance or rheostat and m^{14} is the switch therefor. This switch arm is connected through a bearing sleeve k^1 to a lever k^2 provided with an extension pin k^3 passing through a hole in the shank of the handle of the lever m^{15} ; when the lever m^{15} is moved to change gear, the switch m^{14} is correspondingly moved so as to change the magnitude of the resistance F' interposed in the circuit in accordance with the velocity ratio between the motor spindle and the switch spindle.
- 15 Having now fully described our invention, we declare that what we claim, and desire to secure by Letters Patent is:—
1. In apparatus for operating the feed screw of a reciprocating tool in combination;—a feed screw, a tappet gear actuated by a reciprocating part, a motor adapted to operate the feed screw, a circuit including a source of potential which circuit when closed causes a current to be supplied to operate the motor, a part connected to the tappet gear and to which intermittent movement is imparted by said gear; a part connected to the motor and to which movement is imparted by the motor as the latter actuates the feed screw, and a moving piece articulated to said two parts and to which movement is imparted when there is relative movement between the said two parts, and a switch connected to said moving piece and adapted to control said circuit; substantially as described.
2. In apparatus for operating a feed screw of a reciprocating tool in combination;—a feed screw, a tappet gear actuated by the reciprocating part, a motor adapted to operate the feed screw, a circuit including a source of potential which circuit when closed causes a current to be supplied to operate the motor, a brake device adapted to arrest the motor; an electric circuit to control the brake device; a part connected to the tappet gear and to which intermittent movement is imparted by said gear; a part connected to the motor and to which movement is imparted by the motor as the latter actuates the feed screw, a moving piece articulated to said two parts and to which movement is imparted when there is relative movement between the said two parts, and a switch connected to said moving piece and adapted to control said circuit and the brake control circuit; substantially as described.
3. In apparatus for operating the feed screw of a reciprocating tool, and in combination with the feed screw, a tappet gear, a feed motor geared to the feed screw, a motor energizing circuit, and a switch to control said circuit; means for operating the

- switch comprising a part to which angular movement is given by the tappet gear, a part to which angular movement is given by the motor, a moving piece connected to the switch and actuated by relative movement between the said two parts, and means for regulating the amount of angular movement given to one of the said parts; substantially as described. 5

4. In apparatus for operating the feed screw of a reciprocating tool, and in combination with the feed screw, a tappet gear, a feed motor geared to the feed screw, a motor energizing circuit, and a switch to control said circuit;—means for operating the switch comprising a part to which angular movement is given by the tappet gear, a part to which angular movement is given by the motor, a moving piece connected to the switch and actuated by relative movement between the said two parts, and means for regulating the amount of angular movement given to both of the said parts; substantially as described. 10

5. In apparatus for operating the feed screw of a reciprocating tool, and in combination with the feed screw a tappet gear, a feed motor geared to the feed screw, a motor energizing circuit, and a switch to control said circuit;—means for operating the switch comprising a part to which angular movement is given by the tappet gear, a part to which angular movement is given by the motor, a moving piece connected to the switch and actuated by relative movement between the said two parts; means for regulating the amount of angular movement given to one of the said parts; and a direction changing gear between the motor and the part actuated thereby; substantially as described. 15

6. In apparatus for operating the feed screw of a reciprocating tool, and in combination with the feed screw, a tappet gear, a feed motor geared to the feed screw, a motor energizing circuit, and a switch to control said circuit, means for operating the switch comprising a part to which angular movement is given by the tappet gear, a part to which angular movement is given by the motor, a moving piece connected to the switch and actuated by relative movement between the said two parts; means for regulating the amount of angular movement given to one of the said parts; a resistance to regulate the speed of the motor, a switch connected to the said means and adapted to vary the resistance; substantially as described. 20

7. In apparatus for operating the feed screw of a reciprocating tool, and in combination with the feed screw a tappet gear, a feed motor geared to the feed screw, a motor energizing circuit, a brake device adapted to arrest the motor, a circuit to control the

brake device, a part to which intermittent rotary movement is given by the tappet gear by means of a ratchet gear, means for varying the amount of the rotary movement so imparted, a rotatable part geared to the motor by speed changing and direction changing gear, a moving piece articulated to both said parts and adapted when the former part is moved relatively to the latter part to move the switch to close the motor energizing circuit and to hold it closed till the latter part has been moved through a prescribed angle by the motor whereupon the switch is moved to close the brake controlling circuit; substantially as described. 25

8. In apparatus for operating the feed screw of a reciprocating tool, and in combination with the feed screw, a tappet gear, a feed motor geared to the feed screw, a motor energizing circuit, and a switch to control said circuit;—means for operating the switch, comprising a toothed wheel geared to the motor through speed changing and direction changing gear, and a second toothed wheel to which angular movement is given by the tappet gear; a toothed pinion mounted on a movable axis and gearing with said two wheels and adapted to operate the said switch; means for regulating the amount of angular movement given to the said wheels; substantially as described. 30

9. In apparatus for operating the feed screw of a reciprocating tool, and in combination with the feed screw, a tappet gear, a feed motor geared to the feed screw, a motor energizing circuit, and a switch to control said circuit;—means for operating the switch comprising a bevel wheel geared to the motor through speed changing and direction changing gear; a rotatable bevel wheel to which adjustable angular movement is given by the tappet gear; a bevel pinion mounted on a movable axis and gearing with the said bevel wheels and adapted to operate the said switch; substantially as described. 35

10. In apparatus for operating the feed screw of a reciprocating tool, and in combination with the feed screw, a tappet gear, a feed motor geared to the feed screw, a motor energizing circuit, a brake device to arrest the motor, a brake controlling circuit, a resistance in the motor energizing circuit, a resistance controlling switch, and a main switch adapted in the one position to close the motor energizing circuit and in the other position to close the brake circuit;—means for operating the switches comprising a bevel wheel, gearing connecting said beveled wheel to the motor, said gearing comprising a speed changing gear and a direction changing gear, the former adapted also to operate the resistance regulating switch and a direction changing switch adapted to be operated by the latter; and a bevel wheel to

which adjustable angular movement is imparted by the tool tappet gear; substantially as described.

11. In apparatus for operating the feed screw of a reciprocating tool, and in combination with the feed screw, a tappet gear, a feed motor geared to the feed screw, a motor energizing circuit, and a switch to control said circuit;—means for operating the switch comprising a part to which angular movement is given by the motor, a part to which angular movement is given by the tappet gear, and a moving piece connected to the switch and actuated by relative movement between the said two parts; and means connecting the tappet gear to the part actuated by it comprising a device by which the said movement is imparted before the tappet gear reaches the extreme limits of its stroke; substantially as described.

12. In apparatus for operating the feed screw of a reciprocating tool, and in combination with the feed screw, a tappet gear, a feed motor geared to the feed screw, a motor energizing circuit, and a switch to control said circuit;—means for operating the switch comprising a part to which angular movement is given by the motor, a part to which angular movement is given by the tappet gear, and a moving piece connected to the switch and actuated by relative movement between the said two parts; and means connecting the tappet gear to the part actuated by it comprising a ratchet on the latter part, a pawl and ratchet lever, said lever being actuated by a reciprocating bar connected to the tappet gear and provided with a slot a portion of which is oblique to the direction of motion and a portion of which is parallel to the direction of motion; substantially as described.

13. In apparatus for operating the feed screw of a reciprocating tool, and in combination with the feed screw, a tappet gear, a feed motor geared to the feed screw, a motor energizing circuit, and a switch to control said circuit;—means for operating the switch comprising a part to which angular movement is given by the motor, a part to which angular movement is given by the tappet gear, and a moving piece connected to the switch and actuated by relative movement between the said two parts; and means connecting the tappet gear to the part actuated by it comprising a ratchet on the latter part, a pawl carried by the ratchet lever, a secondary lever adapted to actuate the ratchet lever and to impart to it a regulatable stroke, and a bar actuated by the tappet gear and adapted to operate the secondary lever by means of a slot a part of which is arranged obliquely to the direction of motion and a part of which is arranged parallel to the direction of motion; substantially as described.

tappet gear, and a moving piece connected to the switch and actuated by relative movement between the said two parts; and means connecting the tappet gear to the part actuated by it comprising a ratchet on the latter part, a pawl carried by the ratchet lever, a secondary lever adapted to actuate the ratchet lever and to impart to it a regulatable stroke, and a bar actuated by the tappet gear and adapted to operate the secondary lever by means of a slot a part of which is arranged obliquely to the direction of motion and a part of which is arranged parallel to the direction of motion; substantially as described.

14. In apparatus for operating the feed screw of a reciprocating tool, and in combination with the feed screw, a tappet gear, a feed motor geared to the feed screw, a motor energizing circuit, and a switch to control said circuit;—means for operating the switch comprising a part to which angular movement is given by the motor, a part to which angular movement is given by the tappet gear, and a moving piece connected to the switch and actuated by relative movement between the said two parts; and means connecting the tappet gear to the part actuated by it comprising a ratchet on the latter part, a slotted ratchet lever and pawl, a secondary lever having a slot to take an adjustable pin engaging with a slot in the ratchet lever, said secondary lever being provided with an arm connected to the ratchet lever carrying a pin; and a bar actuated by the tappet gear and having a slot therein, a portion of which is arranged obliquely to the direction of motion, and a portion of which is arranged parallel to the direction of motion, said oblique part being adapted to actuate the secondary lever through the said pin; substantially as described.

In testimony whereof we affix our signatures in presence of two witnesses.
